(57) **CLAIM**

I claim the ornamental design for a bale carrying device, as shown and described.

DESCRIPTION

FIG. 1 is a front perspective view of a bale carrying device. FIG. 2 is a top plan view thereof.

FIG. 3 is a bottom plan view thereof.

FIG. 4 is a left-side elevation view thereof.

FIG. 5 is a right-side elevation view thereof.

FIG. 6 is a front elevation view thereof; and,

FIG. 7 is a rear elevation view thereof.

The broken lines shown represent portions of the bale carrying device that form no part of the claimed design.
